(57) **CLAIM**

The ornamental design for a necklace, as shown and described.

DESCRIPTION

FIG. 1 is a front view of a necklace of my new design; FIG. 2 is a rear view thereof; FIG. 3 is a right perspective view thereof; FIG. 4 is a left perspective view thereof; FIG. 5 is a bottom perspective view thereof; FIG. 6 is a top perspective view thereof; FIG. 7 is a front right perspective view thereof; FIG. 8 is a rear left perspective view thereof; FIG. 9 is an enlarged front view of a lower element of the necklace shown in FIG. 1; FIG. 10 is an enlarged front view of an upper element of the necklace shown in FIG. 1; and, FIG. 11 is an enlarged front right perspective view of the lower element of the necklace shown in FIG. 7. The dot-dash broken lines represent the designation of enlargement views and form no part of the claimed design.
